UNITED STATES PATENT OFFICE

WALTER H. WHEELER, JR., OF STAMFORD, CONNECTICUT, ASSIGNOR TO PITNEY-BOWES POSTAGE METER CO., OF STAMFORD, CONNECTICUT, A CORPORATION OF DELAWARE

ROTARY HAND CANCELER

Application filed April 5, 1932. Serial No. 603,361.

This invention is a novel improvement in rotary hand cancelers or printers particularly adapted for the cancellation of mail in post offices; but may be used in any device 5 for making an impression by means of a rotary or oscillating die.

Heretofore, rotary hand cancelers or stamps have been made in one piece with an inking mechanism mounted therein in such a 10 manner as to render same difficult or slow to remove; or so constructed that it is difficult to prevent the hands of the operator becoming smeared with ink; or so constructed that it has been necessary to remove screws or 15 thumb nuts when removing the inking mechanism which screws may become lost. Same have also been made in two parts, the die and main casing in one part; and the handle, base, and inker in the other; and in such construction 20 the die section is removed and the device inked by rolling the inking section in the ink while holding the handle in the hand. But when a device of such two-part construction has been used for a time, the separable die 23 section develops play at the point where it is separably fastened to the handle section. Toggles, clips, crowned thumb nuts, and other means have heretofore been used as a 28 fastening means, but without obviating the difficulties arising from the development of this play.

The principal object of my invention is to provide an inexpensive readily removable bracket carrying the inking roller which 25 bracket may be held in the canceler frame by a single flat or bow spring, whereby the bracket carrying the inking roller may be readily snapped out of the frame, re-inked, and then snapped back again into position in 30 the frame with a minimum loss of time, there being no parts which might become out of adjustment or which might be lost.

A further object is to provide a hand canceler in which the die and handle are carried 45 by the main frame and the inking roller by a sub-frame, whereby the inking roller may be re-inked rapidly and easily without smearing ink on the hands of the operator, and without removing any parts except the inking sub-frame itself, same being accomplished with-

out making the die and the handle separable. If the die and handle are made separable an almost inevitable play between the two parts develops after the stamp has been in use for 55 a short time, whereas making same non-separable, as in my canceler, rigidity between the die and handle is preserved for the life of the device.

I will explain the invention with reference to the accompanying drawing which illustrates one practical embodiment thereof to enable others, familiar with the art, to adopt and use the same; and will summarize in the claims the novel features of construction, and novel combinations of parts, for which protection is desired.

In said drawing:

Fig. 1 is an end elevation of my rotary hand canceler.

Fig. 2 is a vertical section therethrough.

Fig. 3 is a perspective view of the sub-frame, detached.

As shown in the drawing, my rotary hand canceler or stamp consists of a U-shaped frame 1, in the upper open end of which is 75 rotatably mounted a printing or canceling die 2 journaled on a spindle bolt 1a extending between the legs of the frame. A socket 3 is welded to the base of frame 1, and a handle 4 of wood or other suitable material 80 is forced into the socket 3 and secured therein by pins 4a.

A U-shaped sub-frame 5 is removably and pivotally mounted between the legs of frame 1, said sub-frame carrying pins 6 which are 85 riveted or otherwise secured to the sides of the sub-frame 5, and engage open bearing slots 1b in the legs of the frame 1. The two pins 6 which are riveted to the inking sub-frame 5 have shoulders 6a to locate the assembly in the slots 1b of frame 1, and have cupped heads 6b to afford a good grip for the fingers of the operator. In the sub-frame 5 is rotatably mounted an inking roller 10 of 95 felt or the like journaled on a removable spindle bolt 11 held in place by a shouldered screw 11a. The inking sub-frame 5 is made in the form of a box or hood so that when removed from frame 1 and when rolling the roller 10 in the ink the operator can hold the cupped 100

pins 6a between his thumb and middle finger, press his index finger against the curved base plate 5a of the sub-frame, and roll the ink roller 10 in the ink without getting any of the 5 ink on his fingers. Ink which falls from the roller when the device is in use, or during or after inking, will be caught in the sub-frame 5 and prevented from getting on the hands of the operator.

10 The inking sub-frame 5 is forced against the die 2 by a V-shaped bow spring 7, pivoted around a pin 8 in the frame 1, the lower leg of the spring being prevented from swinging in the frame when the inking sub-frame 15 5 is removed by a pin 9.

The contact points of the ink roller 10, die 2, slots 1b and the position of the pins 6, and the shape of the bow spring 7 are such that the spring 7 will hold the sub-frame 5 firmly 20 in place with the ink roller 10 pressed against the die. To remove the sub-frame, the pins 6 are grasped between the thumb and finger and pulled out. To insert the sub-frame, the pins 6 are grasped as above, and the inker 25 snapped in place by pushing the curved base plate 5a of the sub-frame 5 over the end 7a of the spring 7 and by pushing the recessed portions of the pins 6 into the slots 1b. The free end 7a of spring 7 may be grasped with 30 the thumb while the handle is held in the hand, and pulled downward toward the handle, as an aid in inserting the sub-frame; but it may be inserted very easily by simply forcing the spring 7a downward by means of the 35 curved base 5a of the sub-frame 5 as the roller 10 rolls over the die 2 in the act of directing the sub-frame between the spring 7 and the die 2.

When the ink roller wears out, a new one 40 may be inserted by removing the inker from the device as above, and removing the screw 11a and the spindle 11.

I claim:

1. In a rotary printing device, a frame, a 45 rotary printing die carried by the frame, a removable sub-frame pivotally supported in the frame, an inking device carried by the sub-frame, and common means for yieldably retaining the sub-frame in said frame and for pressing the inking device against the die.

2. In a rotary printing device, a frame, a rotary printing die carried by the frame, a removable sub-frame pivotally supported in the frame, inking devices carried by the sub-frame, and means for normally retaining the sub-frame in said frame with the inking devices engaging the die; one of the frames carrying pins engaging open slots in the other frame.

3. In a rotary printing device, a frame, a rotary printing die carried by the frame, a removable sub-frame pivotally supported in open slots in the frame, inking devices carried by the sub-frame, and means for normally retaining the sub-frame in said slots

and for pressing the inking devices against the die.

4. In a device as set forth in claim 3, said frame being U-shaped and said printing die being journaled in bearings adjacent the outer ends of the legs; and a handle secured to the base of the frame.

5. In a rotary printing device, a frame, a rotary printing die supported therein; a removable sub-frame; an inking roller mounted in the sub-frame, pins on the sub-frame; open slots in the frame receiving said pins; and a spring in the frame engaging the sub-frame for normally retaining the pins in the slots and for pressing the inking roller 75 against the die.

6. In a device as set forth in claim 5, said frame being U-shaped, and said printing die being journaled in bearings adjacent the outer ends of the legs; and a handle secured to the base of the frame.

7. In a device as set forth in claim 5, said sub-frame being U-shaped, and said inking roller being journaled in bearings adjacent the outer ends of the legs; and said pins being mounted on an axis parallel with that of the roller.

8. In a device as set forth in claim 5, said pins having enlarged heads, and the outer faces of the heads being cupped.

9. In a device as set forth in claim 5, said spring being bowed with one end fixed to the frame and the other end engaging the sub-frame, and yieldably pivoting the sub-frame 95 towards the die.

10. In a rotary hand printing device, a U-shaped frame, a rotary printing die journaled therein; a U-shaped sub-frame removably and pivotally mounted in the frame; an inking roller journaled in the sub-frame; aligned pins on the legs of the sub-frame; opposed open slots in the legs of the frame receiving said pins; and a bow spring in the base of the frame engaging the base of the sub-frame for normally retaining the pins in the slots and for pressing the inking roller against the die.

11. In a device as set forth in claim 10, a handle secured to the base of the frame.

12. In a device as set forth in claim 10, said pins being mounted on an axis parallel with the inking roller, and the base of the sub-frame conforming with the curvature of the roller.

13. In a device as set forth in claim 10, said pins having enlarged heads, the outer faces of the heads being cupped.

14. In a device as set forth in claim 10, said spring being substantially V-shaped with one leg fixed to the frame and the other leg engaging the sub-frame, and a pin carried by the frame engaging the apex of the spring.

WALTER H. WHEELER, JR.
